282,659, now Patent No. 233,175. Divided and this
application July 26, 1974, Ser. No. 492,358

Claims priority, application Germany Feb. 25, 1972

Term of patent 14 years

Int. Cl. D26—04

U.S. Cl. D73—1 B

The figure is a side elevational view of a chain candle showing my new design, the appearance being the same from all sides.

This is a divisional application of application Ser. No. D. 282,659, filed Aug. 22, 1972, now issued as Pat. No. D. 233,175 on Oct. 8, 1974.

I claim:

The ornamental design for a chain candle, as shown and described.
